UNITED STATES PATENT OFFICE.

HARRY AGLOW, OF NEW YORK, N. Y., ASSIGNOR TO ARTCRAFT METAL STAMPING CORPORATION, A CORPORATION OF NEW YORK.

DESIGN FOR A LIGHTING-FIXTURE TASSEL.

Application filed January 29, 1925. Serial No. 12,184. Term of patent 7 years.

To all whom it may concern:

Be it known that I, HARRY AGLOW, a subject of the King of Great Britain, and a resident of the city of New York, county of Bronx, and State of New York, have invented a new, original, and ornamental Design for Lighting-Fixture Tassels, of which the following is a specification, reference being had to the accompanying drawing, forming a part hereof.

The figure shows a side elevation of the lighting-fixture tassel.

I claim:

The ornamental design for a lighting-fixture tassel substantially as shown.

HARRY AGLOW.
